BLASTING CONTROL DEVICE

Luther F. Miller, Newburgh, N. Y.

Application October 17, 1947, Serial No. 780,451

11 Claims. (Cl. 175—115)

1

This invention relates to blasting control devices, and more particularly to circuits and apparatus for control of sequential multiple-shot blasting.

In some blasting operations, for example in quarrying or construction work in inhabited areas, there is a definite limitation on the quantity of explosive which can be simultaneously detonated. This limit is principally imposed by the hazard to building structures in the vicinity from excessive earth tremors. It has heretofore been found that, where, as is customary, a plurality of charges are employed, by firing them in rapid sequence instead of simultaneously, comparable or even superior blasting effectiveness can be achieved while limiting the seismic effect to that which would be produced by firing only a single charge of magnitude equal to, or even less than, that of the largest of the several charges. Thus, this sequential or "delayed action" blasting procedure permits the use in each charge of a quantity of explosive equal to the total quantity permitted for a simultaneous multiple-shot blast without any increase in hazard from earth tremors. This results in a considerable increase in the speed and effectiveness of such blasting operations.

Various devices for controlling such sequential blasting have heretofore been used, most of them built around a manually operated multiple-contact switch. In such devices, the time intervals between successive shots is ascertained by the speed with which the movable arm of the switch is actuated by the operator—at best an indefinite and erratic determinant.

Another expedient frequently employed is that of delayed-action caps. These not only are subject to occasional failure, but to inaccuracy and to limitation of the minimum time delay of which they are capable.

It has now been discovered that there exists a somewhat critical time interval between successive blasts in a sequence at which markedly superior results may be achieved. This time interval has been evaluated largely by empirical methods, and depends on such factors as the spacing of the holes in which the charges are placed, the density of the soil or stone, and the like. Within the favorable range of time interval values, there apparently is some interference or cancellation effect between the several compressional waves emanating from the various explosions, which effect materially reduces the amplitude of their resultant or summative wave. Also, for reasons which do not fully appear, the blasted stone is more thoroughly fragmented; this is particularly advantageous in quarrying work, as it lessens or eliminates the after-breaking otherwise required to reduce the stone to the desired size. The above discussed blasting con-

2

trol devices have been found incapable of accomplishing the accuracy of time interval requisite to achievement of these superior results.

It is accordingly among the objects of the invention to provide a control device capable of supplying igniting electrical impulses to a series of blasting charges at definite and uniform time intervals. Another object is that of providing a blasting control device in which the hazard of accidental, premature or anachronistic detonation is substantially eliminated. A more particular object is the provision, in such a device, of means for assuring that the sequence of detonations is commenced at the proper charge in the line of charges. A further object is that of minimizing the length and number of interconnecting cables required among the various units in the system.

These objects and others apparent hereinafter, are accomplished by the present invention, a suitable embodiment of which is described herein and shown in the appended drawings, in which

Figure 1 is a perspective of a blasting site, with a control device embodying features of the invention shown in use; and

Figure 2 is a partially schematic diagram of the principal electrical components of said device.

Referring to Figure 1, a typical quarrying operation is shown in which a control device constructed in accordance with this invention is in use. There is illustrated at A a wall or face of stone on which the blasting is to be performed. As is customary in such practice, a row of vertical holes B is drilled in the upper ground level a short distance behind the face A to receive a series of explosive charges. The spacing between the holes B, their common spacing from the face A and the quantity of explosive used in each hole is determined by such considerations as the nature of the stone, the location of the quarry, the desired size of the fragments and the like. Running along the line of holes B and connected to one terminal of the igniter element of each charge is a common electrical conductor 24, which in turn is connected by means of a conductor 25 with one of the terminals 26 on an output terminal board 28 of a switching unit, generally indicated at C and suitably located some 100 or 150 feet from the row of holes B. The other terminals of the igniter elements are connected by means of separate conductors 27 to one of the terminals 1-20 on the output terminal board 28 of switching unit C.

In order to ascertain whether all of the charges have been fired, i. e. whether any live charges remain unexploded after the firing, it is a frequent practice to employ a camera to photograph the explosions. In Figure 1, such a camera D is shown so located and directed as to view the

entire row of holes B, and it is adapted, by means hereinafter described, to have its shutter tripped and its film exposed immediately after the last of the series of charges has been detonated. Due to the rapidity of the firing and the operation of the camera D, there will appear on the picture taken by camera D a smoke puff or similar visible indication above each of the holes B whose charge has been detonated. It is thus possible to ascertain whether any, and if so which, of the explosive charges has not been fired so that its safe removal may be effected. For purposes of actuating the camera D a two-conductor cable 31 connects the shutter actuating mechanism of the camera with terminals 26 and 30 of output terminal board 28 of switching unit C.

A control unit, generally indicated at E, is located in a protected spot, for example some 150 to 300 feet from switching unit C. The two units C and E are interconnected by means of a four-conductor cable 32 between the input terminal board 33 of switching unit C and the output terminal board 34 of control unit E. With this arrangement, the operator controlling the blasting is located at the control unit E some 250 to 450 feet from the row of charges and out of the range of personal hazard. However, since only a single cable 32 is employed for a major portion of the distance between the operating position and the row of holes B, i. e. from the control unit E to the switching unit C, so that the multiple conductors which fan out to the various holes extend considerably less than half of the total distance, i. e., from the holes B to switching unit C, it will be seen that an economy of length and number of conductors is achieved.

As shown in Figure 2, switching unit C includes a switch, indicated generally at 34, having a plurality, in this case twenty-two, fixed contacts or points 1'-22', arranged in an arc about the axial of a shaft 35 which carries a radial arm 36 arranged to be driven to sweep around said arc and engage said contacts in sequence. Shaft 35 is rotatably mounted on the frame of switching unit C and is arranged to be driven by a suitable electric motor 37 through a variable speed transmission 35a, which may be interposed between the motor and the shaft 35 for controlling the angular velocity of rotary arm 36. The terminals 38 and 39 of motor 37 are connected by means of conductors 40 and 41 with two of the terminals 42 and 43, respectively, on the input terminal board 33 of switching unit C. Terminals 42 and 43 are, in turn, respectively connected by means of two conductors 44 and 45 in the four-conductor cable 32 with two of the terminals 46 and 47 of the output terminal board 34 of the control unit E. Within control unit E, terminals 46 and 47 are each respectively connected to terminals 48 and 49 of the input terminal board 50 of this control unit through one pole of a double-pole-single-throw switch 51. Terminals 48 and 49 of input terminal board 50 provide connections for a suitable source of electric power P. An indicator lamp 52 is connected across terminals 48 and 49 and is illuminated to indicate the availability of electric power at that point. When switch 51 is closed, power will be supplied from the source P to motor 37 through terminals 48 and 49, switch 51, terminals 46 and 47, conductors 44 and 45, terminals 42 and 43, conductors 40 and 41 and terminals 38 and 39, to cause motor 37 to rotate and drive arm 36 continuously. A second indicator lamp 53 may be connected across terminals 46 and 47 in control

unit E to indicate that switch 51 has been closed to supply power to the motor 37. The variable speed transmission 35a is preset to provide that angular velocity of rotary arm 36 which will afford the optimum time interval between successive blasts in the sequence, which interval is determined as hereinbefore described.

The greater portion, in this case twenty, of the fixed contacts 1'-20' of rotary switch 34 in switching unit C are connected by conductors 54 to respectively numbered terminals 1-20 on the output terminal board 28 of switching unit C. For clarification, only one of such conductors 54 has been shown. A brush or similar resilient wiping contact 55 bears against shaft 35 and affords electrical contact from the rotary arm 36 through a conductor 56 to one contact 57 of one pole of a double-pole-single-throw solenoid-controlled switch or relay 58, referred to herein as the safety switch. The contact 59, which cooperates with contact 57, is connected by means of a conductor 60 with the conductor 41 which in turn is connected as previously described to one terminal of the power source P.

One terminal of the solenoid or winding 61 which actuates safety switch 58 is connected to the conductor 40 associated with the opposite terminal of the power source; the opposite terminal of solenoid 61 is connected by means of a conductor 62, a terminal 63 on input terminal board 33, a conductor 64 in cable 32, and a terminal 65 on output terminal board 34 of control unit E to one side of a single-pole-single-throw switch 66, referred to as the firing switch. The opposite side of firing switch 66 is connected by means of a terminal 67 on terminal board 34, a conductor 68 in cable 32, a terminal 69 on terminal board 33, a conductor 70 and the conductor 56 to contact 57 of safety switch 58. One of the contacts 22' of rotary switch 34 is connected by means of a conductor 71 to the conductor 41 associated with the power source.

The operation of this circuit is as follows: when switch 51 is closed, motor 37 is supplied current and runs continuously, driving arm 36 repeatedly around the arc of contacts 1' to 22' at a speed determined by the setting of transmission 35a. Solenoid 61 is not energized as long as firing switch 66 remains open, therefore safety switch 58 remains open and the rotating arm 36 is electrically dead. This is the preparatory or standby condition of the system, and is effectuated immediately prior to firing. The rotary arm 36 will normally make a number of revolutions during this standby period, and, as it repeatedly brushes the fixed contacts 1'-22', it functions to wipe them clean of any dust, corrosion or other impediments so that, before the firing switch 66 is closed, on each revolution the rotary arm is establishing positive electrical engagement with every one of the contacts.

When it is desired to fire the series of charges, firing switch 66 is closed, connecting one side of solenoid 61 to rotary arm 36. This produces no change in the system until the next time the rotating arm 36 engages contact 22'. When this happens, arm 36 and its associated end of solenoid 61 will be electrically connected to conductor 41, effectively bridging solenoid 61 across conductors 40 and 41 and thence across the power source P, and energizing solenoid 61 to close safety switch 58. The closure of switch 58 serves to maintain solenoid 61 energized after rotary arm 36 disengages contact 22', since rotary arm 36 and its associated end of solenoid 61 now are connected

to conductor 41 and therefore to the power source P through contacts 57 and 59 of switch 58. In other words, contacts 57 and 59 function as a "keep alive" for solenoid 61.

Rotary arm 36, being thus connected to conductor 41 and one terminal of the source P accordingly energizes each of the igniter elements on its next sweep past the series of contacts 1'-20'. The return circuit through the igniter elements is completed by the common leads 24 and 25 (Fig. 1) which are connected through output terminal 26 of control switch C and a conductor 72 to one contact 73 of the remaining pole of safety switch 58; cooperating contact 74 of this pole of safety switch 58 is connected by means of a conductor 75 to the conductor 40 and the other terminal of the power source P. The section 73-74 of safety switch 58 functions to open the return circuit through the igniter elements as long as solenoid 61 is deenergized so that neither terminal of an igniter element is connected to the power source until the desired firing time, to eliminate the possibility of accidental detonation by a short circuit in the portion of the circuit associated with one of the terminals of the igniter elements.

Since solenoid 61 is not energized and switch 58 is not closed until the first time rotary arm 36 engages contact 22' after the firing switch 60 is closed, the firing sequence can only commence at the charge associated with contact 1' of switch 34. Also, since the camera is connected to contact 21' of switch 34 its shutter can be tripped only after the entire row of charges has been fired.

Generally, contact 1' of switch 34 will be connected to the charge in the hole at an extreme end of the row of holes B and the successive holes along the row of holes will be connected respectively to the successively numbered contacts of switch 34 so that the charges will be fired progressively along the row of holes B. It has been found that this type of firing produces a tearing or peeling action of the face A, an effect wherein face A gives the appearance of a large stone door swinging open. In this type of action, since the separating force is applied progressively along the face A and is entirely concentrated against the resistance of only a very small portion of the face A at any single instant, efficient separation may be achieved with a good economy of explosive. The contrast between such progressive separation and that which would be effected by firing the entire row of charges simultaneously may be compared to that between removing a strip of adhesive tape from a flat surface on which it is laid down by peeling gradually from one end and by attempting to pull it off at all points simultaneously.

Also, since the cleavage slightly precedes the explosions along the row, as each charge after the first explodes, it expands outwardly against a wall already slightly separated from it and therefore somewhat yielding. The reactive force, which is evidenced as earth tremor, is thus considerably diminished.

In this type of blasting, it is extremely important that the sequence of blasting commences at an extreme end of the row of holes and progresses toward the other, rather than commencing, for example, at the center of the row, working its way to one end, then resuming at the other end and working back toward the middle of the row. The hazard of such a staggered sequence is that the final charges near the center of the row may be completely or

partially exposed before firing with the possible result that stones may be propelled some distance from the blasting site with injury to personnel or property. The characteristic of the control system herein described of incapability of commencing the firing sequence except at a certain point, namely at the charge associated with contact 1' of switch 34, completely eliminates this hazard.

There will thus be seen to have been provided a system which allows the operator at the control unit E to be located at some distance from the row of holes B for complete personal safety, and the switching unit C to be located close to the holes B to achieve economy of cable length, while providing every reasonable assurance against accidental or untimely detonation of charges despite the remote position of the operator with respect to the switching unit C.

Accordingly, it will be appreciated that the present invention accomplishes the aforesaid and other desirable objects. However, it should be emphasized that the description and showing herein is intended as merely illustrative and not as restrictive of the invention.

I claim:

1. A blasting control device comprising a switch having a plurality of contacts arranged in an arc and a rotatable arm operable to engage said contacts in sequence, a safety switch operable to connect said arm to a source of electrical power, a solenoid for operating said safety switch, means to connect said solenoid to said source when said arm engages a certain one of said contacts, an electric motor operatively connected to rotate said arm, and a remotely located switch operable to connect said motor to said source.

2. A blasting control device comprising a multiple contact rotary switch whose fixed contacts are respectively connected to igniter elements of a series of blasting charges, a relay operable to connect the rotary arm of said switch to a source of electrical power, means including a first remotely located switch for connecting the winding of said relay to said source when said arm engages a certain one of said contacts, an electric motor operatively connected to rotate said arm, and a second remotely located switch to connect said motor to said source.

3. A blasting control device comprising a multiple contact rotary switch which has one fixed contact adapted to be connected to one terminal of a source of electrical power, and a plurality of other fixed contacts adapted to be respectively connected to one of the terminals of the igniter elements of a series of blasting charges; a two-pole relay having one pole operable to connect the other terminals of said igniter elements to the other terminal of said source and the other pole operable to connect the rotary arm of said switch to the former said terminal of said source, the winding of said relay being connected between said rotary arm and the latter said terminal of said source; an electric motor operatively connected to rotate said rotary arm; and a remotely located switch operable to connect said motor across said source.

4. A blasting control device comprising a multiple contact rotary switch which has one fixed contact adapted to be connected to one terminal of a source of electrical power, and a plurality of other fixed contacts adapted to be respectively connected to one of the terminals of the igniter elements of a series of blasting charges and

another fixed contact adapted to be connected to the shutter actuating mechanism of a camera, and a rotary arm adapted to engage said fixed contacts in the order named; a two-pole relay having one pole operable to connect the other terminals of said igniter elements to the other terminal of said source and the other pole operable to connect said rotary arm to the former said terminal of said source, the winding of said relay being connected between said rotary arm and the latter said terminal of said source; an electric motor operatively connected to rotate said rotary arm; and a remotely located switch operable to connect said motor across said source.

5. A blasting control device comprising a multiple contact rotary switch which has one fixed contact adapted to be connected to one terminal of a source of electrical power, and a plurality of other fixed contacts adapted to be respectively connected to one of the terminals of the igniter elements of a series of blasting charges; a two-pole relay having one pole operable to connect the other terminals of said igniter elements to the other terminal of said source and the other pole operable to connect the rotary arm of said switch to the former said terminal of said source, the winding of said relay being connected between said rotary arm and the latter said terminal of said source; an electric motor; a variable speed transmission operatively connecting said arm to said motor; and a remotely located switch operable to connect said motor across said source.

6. A blasting control device comprising a multiple contact rotary switch which has one fixed contact adapted to be connected to one terminal of a source of electrical power, and a plurality of other fixed contacts adapted to be respectively connected to one of the terminals of the igniter elements of a series of blasting charges and another fixed contact adapted to be connected to the shutter actuating mechanism of a camera, and a rotary arm adapted to engage said fixed contacts in the order named; a two-pole relay having one pole operable to connect the other terminals of said igniter elements to the other terminal of said source and the other pole operable to connect said rotary arm to the former said terminal of said source, the winding of said relay being connected between said rotary arm and the latter said terminal of said source; an electric motor; a variable speed transmission operatively connecting said arm to said motor; and a remotely located switch operable to connect said motor across said source.

7. A blasting control device comprising a switch having a rotary arm and a plurality of fixed contacts, one of which is adapted to be connected to the first terminal of a source of electrical power and a plurality of the others of which are adapted to be respectively connected to the igniter elements of a series of blasting charges, an electric motor operatively connected to drive said rotary arm, a remotely located switch operable to connect said motor across said source, a relay operable to connect said movable arm to the first terminal of said source, the winding of said relay being connected between said rotary arm and the other terminal of said source, whereby when said rotary arm makes contact with said one fixed terminal, said winding will be energized and said relay will be actuated to maintain the energization of said winding and to connect said rotary arm to said source so that, on the next revolution of said rotary arm, said charges will be serially detonated.

8. A system for testing and controlling the energization of a group of similar electric circuits, comprising a multiple contact switch having a plurality of spaced electrical contacts and a contact arm adapted to move from one contact to the other successively, means connecting said contacts one to each of said similar electric circuits, means for moving said contact arm over said multiple contacts, and means controlled by the motion of said arm over one of said contacts for completing the connection of said contact arm to a power source for energizing said similar electric circuits in successive order according to the travel of said contact arm.

15 9. A system for testing and controlling the energization of a group of similar electric circuits comprising a multiple contact switch having operative connecting means to each of said electric circuits for successively bringing potential to the same from a supply source, an interlocking relay having operative connecting means to apply power to said multiple contact switch, means for operating said multiple contact switch, and means controlled through one of said contacts of said switch for actuating said interlocking relay to apply said power to said contacts.

10 10. A system for testing and controlling the energization of a group of similar electric circuits, comprising a multiple contact switch having a plurality of spaced electrical contacts and a contact arm adapted to move from one contact to the other successively, means connecting said contacts one to each of said similar electric circuits, means for moving said contact arm over said multiple contacts, a remote control switch for said similar electric circuits, and means controlled by the motion of said arm over one of said contacts after said remote control switch has been closed for completing the connection of said contact arm to a power source for energizing said similar electric circuits in successive order according to the travel of said contact arm.

11 11. A system for testing and controlling the energization of a group of similar electric circuits, comprising a multiple contact switch having a plurality of spaced electrical contacts and a contact arm adapted to move from one contact to the other successively, means connecting said contacts one to each of said similar electric circuits, a remote control sweep circuit switch and a remote control switch for the similar electric circuits, means operative by the closing of the sweep circuit switch for moving said contact arm over said multiple contacts, and means controlled by the motion of said arm over one of said contacts after the remote control switch for energizing the similar electric circuits has been closed, for completing the connection of said control arm to a power source for energizing said similar electric circuits in successive order in accordance with the travel of said contact arm.
